(57) **CLAIM**

The ornamental design for a centrifugally cast ductile iron utility pole having stepped portions, as shown and described.

DESCRIPTION

FIG. 1 is an enlarged front elevation view of the present invention, broken at intervals for ease of illustration.

FIG. 2 is a perspective view thereof; and,

FIG. 3 is an enlarged elevation view of one of the stepped portions of the centrifugally cast ductile iron utility pole having stepped portions of FIG. 1.
